MOVING MESSAGE SIGN

Arvid Jansson, Wilkinsburg, Pa.

Application August 9, 1940, Serial No. 351,951

12 Claims. (Cl. 40—32)

My invention relates, generally, to illuminated signs and, more particularly, to electric signs of the moving message type wherein the message to be conveyed is produced by moving a continuous tape or belt in front of a light source or an illuminated area.

Heretofore, many attempts have been made to produce a sign of this type but such prior devices have not been successful for a number of reasons, chiefly because they were of complicated construction, expensive to manufacture and maintain in satisfactory operating condition, were not reliable and of fool-proof construction, and did not function to effect a smooth and steady movement of the message carrying tape or belt past the light source or illuminated area.

Accordingly, it is the object of my invention, generally stated, to provide an illuminated sign of the moving message type which shall be of simple and rugged construction, which may be economically manufactured and maintained in operation, and which shall function over long periods of time to convey the message carried by the belt or tape in a smooth and steady manner.

A more specific object of my invention is to provide a sign of the character described wherein the moving tape is continuously actuated by means of a pair of cooperating grooved rollers or cogwheels only one of which is positively driven.

Another object of my invention is to provide for effecting smooth and steady movement of the continuous tape or belt by drawing it from the magazine through a clearing-out guide and applying a back tension thereto after it leaves the guide and before it passes in front of the light source.

A further object of my invention is to provide for pulling the continuous tape from the magazine by means of a pair of cooperating coglike rollers which feed or discharge the tape directly into the magazine.

A still further object of the invention is to provide for straightening and guiding the folds of the tape from the magazine by means of a clearing-out guide which is movable lengthwise of the magazine to vary the effective length or capacity thereof, and which is so shaped and constructed as to effectively cause the pulled tape to be gradually unfolded and straightened out as it leaves the magazine.

A still further object of the invention is to provide a sign of the character described wherein the moving message is conveyed in a manner to provide a rippling effect to give it an animated

appearance and thereby increase its attractiveness and appeal to those who are viewing it.

Another object of the invention is to provide a drive mechanism for the endless belt of a sign of this character which utilizes a pair of cooperating grooved rollers or cogwheels between which the belt passes, one of which is positively driven and the other functioning as a floating roller.

These and other objects and advantages of the invention will become more apparent when the following detailed description is considered in conjunction with the drawing in which:

Figure 1 is a front view in elevation of a sign embodying the principal features of my invention;

Fig. 2 is a top view of the sign with the top cover removed;

Fig. 3 is an enlarged view in elevation of one of the coglike rollers shown in Fig. 2;

Fig. 4 is an enlarged top view of the fluted rollers;

Figs. 5, 6 and 7 are top, side and end views, respectively, of the clearing-out guide shown in Fig. 2;

Fig. 8 is a cross-section view in elevation of the sign taken along line VIII—VIII of Fig. 2; and

Fig. 9 is a view in elevation of the drag roller of Fig. 1 showing the details thereof.

A sign constituting the preferred embodiment of my invention comprises an elongated housing with an elongated opening in the front thereof covered by a glass or other transparent material, preferably having a ripple finish on the outside thereof. A suitable light source preferably in the form of a tubular lamp, either of the filament or gaseous discharge type, is mounted behind the glass in spaced relation thereto and a suitable reflector utilized to direct light upon the glass. An elongated compartment or magazine is provided within the casing to receive the surplus folds of an endless tape or belt which is perforated to provide the desired message. The tape is driven by means of a pair of cooperating grooved rollers or cogwheels only one of which is positively driven by a motor. The tape is discharged from the rollers or cogwheels directly into one end of the magazine where it accumulates in folds or laps and is pulled from the other end of the magazine through a clearing-out guide over one or more plain rollers, one of which is provided with a brake to place a slight tension on the tape, and between the light source and front cover glass and over another plain roller into the grooved rollers or cogwheels. The tape is

held in a vertical position as it passes by the illuminated window by means of the tension applied, and also by a plurality of guide wires stretched along the front of the light source to provide a narrow vertical guide channel.

Referring now to the drawing, a sign constructed in accordance with the principles of my invention may comprise an elongated rectangular casing 10 provided with a front window or opening 11 covered by a suitable light transmitting medium 12, as plate glass or the like. The casing may be constructed of any suitable material, and is preferably provided with a removable top cover to give access to the mechanism 13 housed within.

The operating mechanism of the sign is shown best in Fig. 2 and comprises an endless belt 14 and a pair of cooperating feed rollers 15 and 16, preferably in the nature of cogwheels, for actuating the belt in a continuous manner past the front window.

The belt 14 may be made of any suitable material, such for example, as book-makers cloth, which is flexible and durable and which will withstand bending and folding and not be appreciably affected by heat. The characters 17 which go to make up the message to be conveyed by the sign when in operation, are formed by perforating the belt, so that a light source placed behind the belt will cause the characters to become illuminated.

The grooved feed rollers or cogwheels 15 and 16 which drive the belt 14, may be driven by a motor 18 mounted within the casing, as shown, and connected in driving relation therewith through the shaft 19 and a worm 20 and worm wheel 21, the latter being shown in Fig. 3. In this instance, only one of the rollers 15 is driven and the other operates as an idling or floating roller. The idling roller 16 cooperates with the driven roller 15 in such manner as to effect a positive drive of the belt without slippage as it functions to provide a wedging action of the teeth or grooves of the rollers upon the belt. This action causes the rollers to take a positive grip upon the belt, which results in a positive driving action and the teeth or cogs of the rollers make uniform folds in the belt and cause it to move in a straight line.

An important feature of the invention is the construction of the feed rollers which, as shown in Figs. 2, 3 and 4, are grooved or creased longitudinally to provide teeth of appreciable depth in order to readily grip and pull the belt. They may be mounted in spaced loosely intermeshing relation on the vertically disposed shafts 22 and 23 which are attached to the bottom of the casing in any suitable manner. The bands or stripper guides 24 which engage the cylindrical spaces 25 between the grooved or toothed sections 26 and which are attached to the vertical supports 27 function to cause the belt 14 to be properly discharged from the feed rollers and prevent it from becoming tangled or carried around the rollers so as to jam the mechanism.

In order to provide for storing or collecting the excess length of belt, the casing is provided with a compartment 30 which may be termed a magazine. As shown in Fig. 2, the feed rollers 15 and 16 are positioned at one end of the magazine 30, and discharge the belt directly therein in folds. When the belt is pulled by the feed rollers 15 and 16, it unfolds and feeds out of the opposite end of the magazine as will be described more in detail hereinafter.

To obtain the proper unfolding of the belt 14 as it is pulled out of the magazine, there is provided a clearing-out guide 31 which may be positioned along the length of the magazine to provide the necessary effective space for the excess belt.

The construction of the guide 31 is also an important feature of the invention as its function is to properly guide the belt from the magazine 10 in a smooth and steady manner and gradually straighten out the folds which have been formed therein by the feed rollers. It is preferably constructed of a length of wire bent into the shape shown in Figs. 5, 6 and 7. The width of the guide 15 is such as to fill the space between the side walls 32 and 33 of the magazine, and it is of such length as to permit the belt to unfold and straighten out properly as it passes therethrough.

With reference to Fig. 6, which is an end view 20 of the guide, it will be seen that the entry end is V-shaped and formed by the members 34 and 35, and that the discharge end which is formed by vertical members 36 and 37 and spaced therefrom is in the form of a slit of uniform width. The purpose of this arrangement of entry and 25 discharge parts of the guide 31 is to permit a certain amount of oscillatory movement of the belt while it is entering the guide in order that it will unfold properly. The V portion functions 30 to provide this result and the slit finally brings the belt into the desired vertical or edgewise operating position.

In order to support and guide the belt 14 past the front window of the casing, a plurality of 35 guide rolls 38 and 39 located at opposite ends of the window, are utilized to support the belt in a vertical position for edgewise movement. A plurality of guide wires 41 to 48 inclusive, may also be used to maintain the length of belt between 40 the guide rolls 38 and 39 in a vertical position without subjecting it to too much tension. As shown best in Fig. 8, the guide wires 41 through 44 are positioned in front of the belt and wires 45 through 48 behind the belt longitudinally of 45 the casing to define a narrow path for the belt to follow. The guide wires may be conveniently supported by the vertical posts 49, 50, 51 and 52 mounted within the casing. If desired, either 50 pair of the posts 49—50, 51—52 may be pivotally mounted so that one set of the guide wires may be moved outwardly away from the belt to facilitate threading the belt over the guide rollers 38 and 39.

With a view to causing the belt to travel in a 55 steady manner and maintain a fairly straight line between the guide rollers 38 and 39, provision is made for subjecting it to an adjustable tension by means of a tensioning or drag roller 53 over which the belt passes as it emerges from 60 the magazine. This roller may also be mounted on a vertical post 54 and subjected to a drag by means of a washer 55 held against the top of the roller by a coil spring 56 disposed on the end of the post, the tension of which is adjusted by a nut 57 engaging the threaded end of the post. The belt also passes over an idler roller 58 mounted adjacent the drag roller 53.

In order to provide for illuminating the belt 65 as it passes behind the window to make the characters readable, a light source 59 is mounted within the casing below the belt and is preferably provided with a reflector 61. While any suitable source of light may be used, it is preferable to use an elongated lamp or plurality of 70 such lamps mounted in end-to-end relation,

which effectively light the front window over its entire length in a uniform manner.

If it is desired to give the moving message conveyed by the belt a rippling appearance, the light transmitting cover 42 may be made of glass, such as Colonial glass, having a rough nippel finish on one side thereof, preferably on the outside surface.

If desired, the casing 10 may be ventilated by means of a fan or blower 62 mounted on the motor shaft, as shown in Fig. 2.

In view of the foregoing, it will be apparent that I have provided a moving message sign or display device which is of simple and economical construction, and which will function to produce an effective and steady display of the message carried by the moving belt. The drive mechanism of the belt is of simple construction and functions to provide a positive and steady pull on the belt. The use of the grooved or cog-like feed rollers makes it possible to obtain a positive and steady pull on the belt without clamping the rollers tightly together upon the opposite sides of the belt and thereby greatly reduces the friction and power required to operate them. This is a distinct advantage when it is desired to operate the sign continuously over long periods of time. The nature of the drive, and especially the shape of the feed rollers, also strengthens the life of the belt and imparts to it the proper movement to secure its desired distribution within the magazine.

The desired movement of the endless belt and its successful movement in and out of the magazine results from the particular combination of elements which make up the drive mechanism, i.e., the grooved or coglike feed rollers, only one of which is positively driven, the stripper guides, the clearing-out guide, the drag roller and the guide wires. The use of the drag roller and guide wires stretched along the illuminated window makes it possible to obtain steady edgewise movement of the belt without subjecting it to excess pull or tension by the feed rollers. Accordingly, the feed rollers are not overloaded and function easily at all times to move the belt in a continuous fashion. The nature of the feed rollers, i.e., their grooved or toothed contour and single roll drive, effectively manipulate the belt as it is discharged into the magazine to cause its proper folding therein so that a maximum length of belt may be stored in a minimum space, and so that the belt will unfold properly when subjected to a slight pull by the feed rollers. The stripper guides function to prevent the belt from jamming as it leaves the feed rollers and the clearing-out guide to effectively unfold and straighten the belt so that it will not jam or tangle as it leaves the magazine.

Therefore, it will be apparent that my invention provides a moving message sign which has many outstanding structural and operational features not found in signs used heretofore, and which are important from the standpoint of successful and economical operation over long periods of time.

While I have shown and described a particular embodiment of my invention, it will be obvious to those skilled in the art that changes and modifications may be made within the scope of the invention, and I, therefore, aim in the appended claims to cover all such changes and modifications that fall within the true spirit and scope of my invention.

I claim as my invention:

1. A moving message sign comprising a relatively long endless belt having characters defined by perforations thereon, a light source, means for guiding the belt past the light source, a magazine for holding the excess slack in the belt, means for actuating the belt, and means for guiding the belt out of the magazine, said guide means being adjustably mounted for movement along the length of the magazine.

2. A moving message sign comprising, a relatively long endless belt having characters defined by perforations therein, a light source, roller members over which the belt passes for guiding it on edge past the light source, a magazine for receiving and holding the excess length of belt, means for pulling the belt out of the magazine past the light source and discharging it back into the magazine in a continuous manner, and guide means disposed in said magazine and movable along the length thereof to adjust the effective length of the magazine in accordance with the length of the belt in use.

3. An electric sign of the moving message type comprising, an endless belt provided with perforated characters, means for illuminating a portion of the course of travel of the belt, means for driving the belt including a pair of coglike rollers mounted in loosely intermeshing relation to receive the belt, a guide roller disposed at each end of the illuminated course of travel to guide the belt thereby in an edgewise position, and a plurality of guide wires stretched along the illuminated portion of the course on opposite sides of the belt for supporting the belt in an edgewise position.

4. The combination in a moving message sign having an endless message carrying belt mounted for movement past an illuminated area of predetermined length, a magazine for storing the excess length of belt in a folded condition, and means for driving the belt, of guide means disposed in the magazine and functioning to assist in the unfolding and straightening operation of the belt as it leaves the magazine, said guide means having a V-shaped entrance portion and a slot-shaped discharge portion, and a tensioning roller engaging the belt between the guide means and illuminated area operable to subject the belt to a drag or braking action to provide a predetermined degree of tautness in the belt as it passes by the illuminated area thereby to further straighten the belt and effect a steady movement thereof.

5. The combination in a moving message sign having an endless message carrying belt mounted for movement into and out of a storage magazine past an illuminated area of predetermined length, of a pair of fluted rollers between which the belt passes for driving the belt, means for driving at least one of said rollers, said belt being discharged into the magazine in a folded condition by said rollers, and guide means positioned within the magazine at its discharge end through which the belt passes while being pulled by the rollers for guiding the belt out of the magazine in a straightened condition, said guide means having spaced entry and discharge ends, the entry end being V-shaped and the discharge end slit-shaped.

6. A moving message sign comprising, an endless belt, a light source, and means for moving said belt past the light source, said means including a pair of cooperating cog wheels rigidly

mounted in loosely intermeshing relation, said cog wheels having relatively deep tooth portions to provide for gripping the belt over a relatively large area, whereby the belt is positively driven without clamping the cog wheels tightly together.

7. A moving message sign comprising, an endless belt, a light source, motor-operated means for moving said belt past the light source, said means including a pair of cooperating coglike rollers mounted in spaced loosely intermeshing relation to engage the belt, at least one of said rollers being positively driven, said rollers being sectionalized to provide a plurality of smooth sections between toothed sections, and stripper guides positioned in said smooth sections to cause the belt to be positively discharged from the rollers.

8. A moving message sign comprising, an endless belt of opaque material having perforations therein in accordance with the characters to be shown, said belt being guided for movement in a predetermined manner past an area of predetermined length, a light source positioned to illuminate the belt over said area, a magazine for accumulating the slack in the belt, a pair of cooperating coglike rollers disposed in intermeshing relation to engage the belt for pulling it from the magazine past the illuminated area, means for driving one of said rollers, and guide means mounted adjacent the rollers for positively guiding the belt into the magazine in a folded condition.

9. A moving message sign comprising, an enclosure having an elongated window, a relatively long endless belt mounted for edgewise movement past the window, a magazine within the enclosure for accumulating the belt, a light source mounted within the enclosure for illuminating the belt as it passes the window to produce a display of the characters on the belt, a driving mechanism for the belt including a pair of rigidly mounted cooperating cog-like rollers disposed to engage the belt in an edgewise position, said rollers being disposed in loosely intermeshing relation, and a plurality of stripper guides mounted intermediate the ends of the rollers for controlling the discharge of the belt therefrom.

10. A moving message sign comprising, an enclosure having an elongated window, a relatively long endless belt mounted for edgewise movement past the window, a light source mounted within the enclosure for illuminating the belt as it passes the window to produce a display of characters on the belt, a magazine for accumulating and hold-

ing the slack in the belt, a pair of cooperating loosely engaging cog-like rollers engaging the belt in an edgewise position over a portion of its entire width for pulling the belt out of the magazine and discharging it therein, said rollers having spaced smooth sections intermediate their ends, guide members positioned in said sections and extending outwardly toward the sides of the magazine, and means for positively driving one of said rollers to produce continuous movement of the belt, said other roller functioning as an idler and cooperating with the driven roller to clamp the belt therebetween and discharge it into the magazine in a folded condition.

15. 11. A moving message sign comprising, a housing having a light source therein and a window in one side thereof, an endless belt having characters defined by perforations therein and disposed for movement between the light source and window to display said characters, a magazine for holding the excess length of belt, means including intermeshing cog-like rollers for actuating the belt, said belt being discharged into the magazine in a folded condition, means engaged by the belt on the outlet end of the magazine for subjecting the belt to a tension as it is moved past the window, and a clearing out guide positioned within the magazine to cause the belt to be unfolded in a straightened condition as it leaves the magazine, said guide being movable along the length of the magazine to vary the effective length thereof in accordance with the length of the endless belt being used.

12. An electric sign of the moving message type comprising, an endless belt provided with perforated characters, means for illuminating a portion of the course of travel of the belt, means for driving the belt including a pair of loosely intermeshing cog-like rollers mounted in side-by-side relation to receive the belt and means for driving one of said rollers, a guide roller disposed at each end of the illuminated course of travel to guide the belt thereby in an edgewise position, and a plurality of slender guide members disposed in vertically spaced relation between said guide rollers on each side of the belt to provide a guideway for supporting the belt in edgewise position as it passes over said illuminated course of travel, thereby to reduce the tension required on the belt to maintain it in an edgewise position to properly display the characters.

ARVID JANSSON.
